ROBERT MACKINLAY SMITH, OF KELVINSIDE, SCOTLAND.

MACHINE FOR POLISHING BOOTS OR SHOES.

1,032,866.

Specification of Letters Patent. Patented July 16, 1912.

Application filed October 6, 1908. Serial No. 456,510.

To all whom it may concern:

Be it known that I, ROBERT MACKINLAY SMITH, a subject of the King of Great Britain and Ireland, of 3 Westbourne Terrace, Kelvinside, in the county of the city of Glasgow, Scotland, civil engineer, have invented certain new and useful Improvements in Machines for Polishing Boots or Shoes, of which the following is a specification.

10 One object of my invention is to provide a novel construction and arrangement of parts for polishing the sides and front of a shoe, it being especially desired that the resulting machine shall be substantial and 15 compact as well as reliable and efficient in operation.

Another object of the invention is to provide a machine having the above characteristics in which revolving brushes are used to 20 clean and polish the sides and heel of the shoe while traveling bands are employed to polish the upper parts of the front thereof; the arrangement being such that there is but little likelihood of said machine getting out 25 of order or requiring any but a minimum of attention and repairs.

I further desire to provide a machine of the class noted with novel operating and controlling mechanism for the side and 30 front polishing devices.

These objects and other advantageous ends, I secure as hereinafter set forth, reference being had to the accompanying drawings in which;

35 Figure 1 is a vertical section of a machine constructed according to my invention; Fig. 2 is a plan, partly in section, illustrating the detail construction of the mechanism and other parts constituting one half 40 of the machine, or that part thereof for operating on one shoe, the other half being a duplicate of that shown; Figs. 3 and 4 are elevations, partly in section, taken in planes at right angles to each other, and illustrating the detail construction of the brush carriages and their associated parts; Fig. 5 is a plan, partly in section, of the apparatus for polishing the front of a shoe; Figs. 6 and 7 are a side and an end elevation of the 45 apparatus shown in Fig. 5; Figs. 8 and 9 are respectively a side elevation and a vertical section of certain details of the carriage reversing mechanism; Fig. 10 is a plan of a portion of the brush-controlling ratchet mechanism and; Fig. 11 is a transverse sec-

tion on the line 8--8, Fig. 5 illustrating in detail the reversing mechanism.

I preferably make my machine with two complete equipments of apparatus so that it can simultaneously operate on both shoes 60 of the user, although in the following description I will refer to but one of these combinations of mechanism.

In the above drawings, 1 represents an inclosing casing for the apparatus hereafter described and this is provided at its front with an opening 2 through which the leg and foot of the user may be introduced. For supporting the foot while the shoe is being operated on, I provide on the platform 9 70 of the machine a set of rails 115 extending into the casing 1, and on these I mount a sliding support or standard 8 whose top parts are checked to properly engage and hold the heel of such shoe. 75

Mounted in bearings within the casing 1, is a transversely extending power shaft 10, driven from a suitable motor (not shown) through a belt 11. On the floor of the casing are provided a suitable number of transversely extending rails or tracks 35 on which are guided the supporting wheels 34 of two frames, each of which consists of a brush carriage 13 and three parallel shafts, 12, 14 and 28 with their various associated fittings 80 hereafter described. Said shafts extend longitudinally of the casing, and those indicated at 14 and 28 are threaded for the greater portions of their lengths; the shaft 12 being provided with a longitudinally extending groove 30. For imparting motion to these shafts I provide two intermeshing beveled gears 117 of which the first is splined to the shaft 10, and the second is fixed to the shaft 12. This latter also has 90 fixed to it two gears 49 and 51, while the shaft 28 has splined to it a clutch sleeve 46 carrying two gears 47 and 48. The first of these is capable of meshing with the gear 49 when the sleeve 46 is in one position, and 100 when it is in the second position said two gears 47 and 49 are out of mesh, while the gear 48 meshes with an intermediate gear 50 which at all times meshes with the gear 51. On the shaft 28 is also fixed a sprocket 105 wheel 15 which is operatively connected by means of a chain 16 with a second sprocket wheel 15^a fixed to the shaft 14.

The brush carriage 13 may be described as consisting of a bracket structure 27 hav-

ing nuts 31 for the reception of the shaft 28 and also having an opening with a key whereby it is splined to the shaft 12. A second nut structure 31^a is threaded on the shaft 14 and with the bracket 27 provides bearings for a spindle 23. On this latter are loosely mounted two sets of arms 21 and these in turn provide bearings for four spindles respectively carrying three brushes 17, 18 and 19, together with a buffing roll 20. Each of said four spindles has fixed to it a gear wheel 22 and all of these gear wheels mesh with another gear wheel 52 fixed on the central spindle 23, which also has fixed to it a sprocket. This sprocket is connected by a chain 24 with a sprocket on the boss 25 of a beveled gear wheel 26 carried by the bracket 27 in such manner as to mesh with the second beveled gear 29 splined to the shaft 12.

For the purpose of compelling the brush carriage to turn in but one direction I provide a ratchet wheel 65 on a boss or hub 116 fixed to the arm structure 21 and mount on the nut structure 31^a of the shaft 14 a spring pawl 66 in such a position as to engage said ratchet wheel. The brushes 18, 17 and 19 are respectively a hard brush for cleaning dust from the shoes, a blacking brush and a polishing brush, while the buffing roll 20 is made of any suitable material. In order to provide the brush 17 with blacking, I provide an annular reservoir 32 for blacking, fitting it around the central spindle 23 of the brush carriage 13 and connecting to it a duct 33 extending parallel with said spindle 23. This duct is perforated on the side immediately adjacent the brush 17 to which it is designed to supply blacking, so that a proper supply of the latter is provided for said brush. The carriage 13 with its shafts 14, 12 and 28 and their various fittings, being supported on the small wheels 34, is normally drawn toward the shoe to be operated on, by weights 36 which are connected to it through cords 37. These cords pass around pulleys 38 so that they act in the desired directions, and as above indicated, the shaft 10 is grooved to permit of the beveled gear wheel 117 sliding thereon as the brush carriage with its shafts and other structures is moved toward or from the shoe.

In Fig. 2 I have shown one of the brush carriages with its associated parts in the inner position, and the other as in its outer position; it being obvious that as said brush carriages are moved longitudinally they are likewise moved transversely of the casing in order that their brushes may follow the contour of the shoe operated on. The carriage bracket 27 is provided with two projections 54, through both of which passes a gear changing rod 40 extending longitudinally of the casing 1 and slidably mounted in suitable bearings in the main-shaft-supporting

frame adjacent the clutch sleeve 46. Said rod 40 has an arm 45 engaging this sleeve so as to be capable of moving it in order to bring into mesh the gears 47 and 49 or the gears 48 and 50. This rod 40, adjacent the arm 45, has an abutment with a spring 41 and a disk 39, so placed as to be engaged by one of the projections 54 of the brush carriage when this approaches one end of its path of movement. Similarly on the other end of the rod 40 is mounted an abutment having a spring 56 and a second disk 39 placed to be engaged by the second of the projections 54 of the brush carriage. In addition there are fixed to the bracket structure 27 of the brush carriage two arms 42 and 57, the first of which is so placed as to be capable of engaging a lever 43 to operate a catch 44 normally engaging a notch in the rod 40. The arrangement of parts is such that after the projection 54 has compressed the spring 41 to a predetermined extent said arm 42 engages the lever 43 and raises the catch 44 out of the notch in said rod, thereby permitting it to move longitudinally under the action of said spring, a sufficient distance to shift the clutch sleeve 46. The opposite end of the rod 40 is also provided with a notch capable of being engaged by a latch 55 so placed as to be actuated by the rod 57 when the brush carriage has moved to a point adjacent the second end of its path of movement. The arrangement of parts is such that after the second projection 54 has compressed the spring 56 to a predetermined extent, the arm 57 disengages the latch 55 from the shaft 40, allowing it to move under the action of the spring 56 a sufficient distance to move the clutch sleeve 46 in a direction opposite that heretofore noted, for a distance sufficient to bring the gears 49 and 47 into engagement.

The rotatable brush carrying arms of the carriage 13 are provided with a series of four pins 61 and there is mounted on the carriage-and-shaft-supporting structure a pair of forked abutments 62 and 62^a so placed that as the brush carriage approaches one end of its path of movement, one of the pins 61 strikes the forked abutment 62, with the result that the arms 21 and with them the brushes which they carry are turned through an angle of substantially 90 degrees. Similarly at the opposite end of its path of movement another pin 61 engages the forked abutment 62^a so that the brushes are again turned in the same direction as before through an arc of 90 degrees. Each of the abutments 62 and 62^a is pivotally mounted and yieldingly held in a definite position by a spring so that its forked end is free to follow the curved path taken by the in 61 as it is moved.

While the ratchet wheel 65 and its pawl 66 insures that the brush carriage shall turn

in but a single direction, it is advisable to provide means whereby it shall be prevented from turning more than 90 degrees under the action of the abutments 62 and 62^a and shall be held when so turned. For this purpose there are on the brush carriage four projecting lugs 64, and a pivoted trip bolt 63 designed to coöperate therewith, and pivotally mounted on a portion of the nut structure 31^a. This trip bolt 63 is normally held from turning on its pivot by a lever 69 engaging one of its ends and also supported in a suitable manner on the nut structure 31^a. On this lever 69 is a roller 67 so placed as to be capable of engaging one of two abutments 68, when the carriage approaches either end of its path of movement. By such engagement the lever 69 is swung on its pivot out of engagement with the trip bolt 63, which is thus free to turn on its supporting pivot and permit the passage of one of the projecting lugs 64 with consequent rotation of the brush supporting structure of the carriage 13.

The above described parts are designed to operate on the sides and heels of a shoe, and for polishing the front and top of the shoe I provide a substantially rectangular frame 70 loosely mounted on a supporting shaft 84, operative in bearings in the ends of a pair of arms 71. These latter are fixed to sleeves 72 rotatably mounted on a supporting shaft 73 which in turn is mounted in bearings in suitable brackets supported by the casing 1. The shaft 84 extends coaxially with the frame 70 so as to turn independently thereof and is driven through a pair of beveled gears 83 from a shaft 82 supported on one of the arms 71. A second pair of beveled gears 81 operatively connect this shaft 82 with the shaft 73 and this in turn is driven from the main shaft 10 through a chain 80 and a pair of sprocket wheels; the arrangement being such that said shaft 84 is turned regardless of the position of the arm 71.

Through a pair of beveled gear wheels 86 power is transmitted from the shaft 84 to a second shaft 87 mounted on the frame 70 so as to extend at right angles thereto, and said second shaft has fixed to it a pair of pulleys 85 connected by belts or cords to two other pulleys 85^a and 85^b respectively fixed to the shafts of two band supporting rollers 75^a and 75^b mounted at opposite ends of the frame 70. Each of the said ends of the frame has in addition two other rollers 76 and 77 which with the rollers 75^a and 75^b as the case may be, serve to support two traveling bands 74 of woolen, felt or other suitable material. It is to be noted that the rollers 76 are provided with spindles carried by blocks 77 slidably mounted in slots 78 of the frame 70, and said blocks are at all times acted on by tension springs 79 so as to

keep the bands 74 always under tension, or in a tight condition.

One of the bands 74 is designed to apply blacking to the front of the shoe, while the other is for the purpose of polishing, and in order to alternately bring said bands into engagement with the top of the shoe I provide a gear wheel 88 loosely carried on the shaft 84, and mount on the casing 1 a curved, toothed rack 89 in such a position as to be engaged by teeth of this gear wheel 88 when the arms 71 are so turned on their supporting shaft 73 as to raise the frame 70 and its attached parts. For this purpose the gear wheel 88 is connected to the frame 70 by a suitable pawl 88^a, so arranged that the frame 70 is turned on its axis through an angle of 180 degrees as it is raised by the arms 71 but is held by locking means hereafter described while the gear 88 turns independently as the arms are lowered.

Blacking is supplied to one of the bands 74 from a blacking pad 104 which is connected to a reservoir, and is supported by the casing 1 in any suitable manner in such position that said band engages its flat surface when the frame 70 is raised to the required height. In order that both of the bands 74 may not engage the blacking pad, the shaft 84 and hence the axis of the frame 70, is arranged to one side of the center line of said frame so that the distance from said shaft to the outer part of the band 74 which is designed to receive blacking is slightly greater than that to the outer part of the polishing band. Since the arms 70 are elevated, by the mechanism hereafter described, to the same height at each operation, the blacking band is caused to engage the supply pad 104 when the band carrying frame is raised, while the polishing band is never brought into engagement with said pad.

In order that the frame 70 shall be held steady or locked in place after each of its half revolutions, I mount on one of the arms 71 a longitudinally movable rod 91, having a pin 90 hinged to one of its ends in position to be capable of entering either of two holes 95 in said frame 70. For the purpose of longitudinally moving this rod against the action of a spring 94, to withdraw the pin 90 from one of these holes, in the frame 70, I mount on a web 96 connecting the arms 71, a lever 92, one of whose ends is pivoted to the rod 91 while the other has hinged to it a pawl placed to be engaged by a roller 93 carried on a suitable bracket of the shaft supporting structure. This pawl is so arranged that as the arms 71 with the band frames are raised, it engages the roller 93 and turns the lever 92 on its fulcrum thereby moving the rod 91 and withdrawing the pin 90 from engagement with the frame 70 before the gear wheel 88 engages the toothed rack 89. As soon as the said pawl has

passed the roller 93 the spring 94 acts on the pin 90 to tend to return it to the hole 95 of the frame 70. This however cannot occur until said frame has been turned 5 through 180 degrees, after which the pin enters said hole and rigidly holds the frame in its given position. As the arms with the frames are lowered, the pawl of the lever 92 merely turns on its hinge when it comes in 10 engagement with the roller 93 so that the pin 90 is not affected.

For the purpose of raising the frame 70 and its attached parts I provide a pair of cords 98 connected through the web 96 to the arms 71 and pass said cords over pulleys mounted on brackets carried by the casing 1, attaching weights 114 to their ends, for the purpose of drawing or holding down the arms with their frame. Fixed to 15 the shaft 73, is a curved segment 97 having connected to it one of the cords 113, which passes around a pulley 99 mounted on the structure which supports the shafts 12, 28 and 13 and at its opposite end, connected to 20 a carriage 100, movable longitudinally of the casing 1. A rail 101 is mounted on said shaft carrying structure so as to extend parallel to the shaft 14 and on the side of this rail is mounted a ratchet 103 in such 25 a position that its teeth may be engaged by a pawl 102 on the carriage 100, when this latter is in such a position that through the cord 113 it holds the band supporting frame 70 in its lowermost position. This carriage 30 100 has pivoted to it a lever 109 and also a projecting member 106 forming a cam. The nut structure 31^a heretofore referred to has pivoted to it a lever 105 capable of 35 engaging a notch or recess of said cam 106 from which it may be disengaged by the action of a projection 112 forming an abutment which is supported in any suitable manner. The lever 109 is capable of engaging the pawl 102 so as to retain it in engagement with the ratchet 103 and for the 40 purpose of actuating this lever, I provide a trip bolt 108 on the nut structure 31^a.

With the above described arrangement of parts, the main shaft 10 may be driven from 45 any desired source of power and if the user of the machine places his foot upon the structure 8 and moves it with the same into the position shown in dotted lines in Fig. 1, the sides of the shoe will first be cleaned 50 by the brush 18. In order that this operation shall be carried out, the carriage 13 on each side of the shoe is moved longitudinally of the casing by reason of the fact that power is transmitted from the shaft 10 55 through the gear wheels 117, through the shaft 12, thence through the gear wheels 51, 50 and 48 to the shaft 28 and through the sprocket wheels 15, chain 16 and sprocket wheel 15^a to the shaft 14. Since 60 this latter as well as the shaft 28 is thread-

ed, the carriage 13 is moved longitudinally of the shoe, and all of the brushes are turned on their spindles by power received from the shaft 12 through the gear wheels 29 and 26, the sprocket wheel 26, chain 24, 70 sprocket wheel, spindle 23 and gear wheels 52 and 22.

Owing to the action of the weighted cords 37, both the brush carriages 13 are pressed toward the shoe at all times so that the 75 brushes acting thereon are actuated to properly perform their work. As each brush carriage approaches the front end of the casing, one of its pins 61 strikes a forked structure 62^a and during the last part 80 of its forward movement the arms 21 with their brushes are turned about the spindle 23 as an axis through an angle of 90 degrees; the pawl 66 yielding to permit such 85 turning.

Just before the pin 61 engages the forked structure 62^a the abutment 68 strikes the roller 67 of the lever 69, thereby turning this latter so as to release the trip bolt 63 and permitting one of the lugs 64 on one of 90 the arms 21 of the carriage to pass. By the time that the brushes and their supporting structures have made their 90 degree turn, the lever 69 has again engaged the trip bolt 63, so that it engages the next lug 64 and 95 prevents further turning of the brushes. As the brush carriage approaches the forward end of its path of movement, the projection 54 first engages the disk 39 and after compressing the spring 56 brings the 100 arm 57 into engagement with the latch 55, thus freeing this latter from the notch in the rod 40. Said rod thereupon moves longitudinally under action of the spring 56 and through the arm 45, shifts the gear 48 105 out of engagement with the gear 50 and brings the gear 47 into engagement with the gear 49. As a consequence, the direction of rotation of the shafts 28 and 24 is reversed and both brush carriages are 110 started toward the rear end of the machine, each with its second brush 17 in position to engage the sides of the shoe.

When the carriage has moved to within a predetermined distance of the rear end of 115 the casing, its lever 69 is again engaged by one of the abutments 68, thus freeing the carriage from the restraint of the trip bolt 63 and permitting the brush carrying structure to be turned through another 90 degrees, by reason of engagement of a second one of the pins 61 with the forked abutment 62. Since the brush 17, as before noted, receives blacking from the reservoir 32 and tube 33, such blacking is applied by it to 120 the sides of the shoe, so that when the brush carriage is again started forward, its third brush 19 acts to remove the surplus blacking and give a first polish to said shoe. Reversal of movement of the carriage is ac- 125 130

complished by reason of the longitudinal movement of the rod 40 as caused by the projection 54 compressing the spring 41, and the subsequent release of the catch 44 from said rod under action of the arm 42 on the lever 43; such movement of the rod moving the gears 48 and 50 out of mesh and the gears 47 and 49 into mesh. Another reversal of movement of the carriage is accompanied by the bringing into action of the buffing roll 20 and after the final polishing of the sides of the shoe by this latter, the motive power is cut off from the belt 11 by any of the well known mechanisms to bring the machine to rest. It is to be noted, however, that as the brush carriage for the first time moves toward the front of the machine, the lever 105 thereafter comes into engagement with the cam projection 106 thereby causing the small carriage 100 to move along the rail 101 and through the cord 113 drawing down the band carrying frame 70 against the action of the weights 114. That one of the bands 74 which is capable of engaging the blacking pad 104 is thus brought into engagement with the front and top of the shoe to be polished and is made to assume the position shown in Fig. 7, the tension spring 79 yielding to permit the roller 76 to move into a corresponding position. When the carriage 100 has been so far moved that the band 74 occupies the position above indicated, it is retained therein by reason of the engagement of the pawl 102 with the teeth of the ratchet 103. At such time the abutment or projection 112 strikes the roller 111 on the end of the lever 105, thus raising this latter out of engagement with the projection 106. The brush carriage is thereafter free to continue its forward movement independent of the carriage 100, and during such movement the band frame remains in the position shown in Fig. 1. Both bands 74 are continuously driven from the shaft 10 through the chain 80, shaft 73, gear wheels 81, shaft 82, gear wheels 83, shaft 84, gear wheels 86, shaft 87, and pulleys 85 and 85^a, with their associated bands or belts. As the brush carriage is moved toward the rear of the machine, however, the lever 105 slides up on the inclined face of the projection 106 on carriage 100 and falling behind the same, holds said latter carriage while the lever 109 is moved by the trip bolt 108 so that it finally frees it from the pawl 102 which thereafter swings out of engagement with the rack 103. The carriage 100 then moves to the rear with the brush carriage and in so doing permits the arms 71 with the band frame 70 and its parts to rise under the action of the weighted cords 98. After the frame is unlocked by the roller 93 acting through the lever 92 and rod 91 on the pin 90, the gear 88 by co-acting with the toothed rack 89, turns the band frame 70 on the shaft 84 through 180 degrees, finally bringing the blacking band into engagement with the blacking pad after said pin has again entered one of the holes 95 to lock said frame in position. As the brush carriage again moves toward the front of the machine, it again carries with it the carriage 100, thus pulling down the band frame, which this time, has its polishing band in position to engage the front and top of the shoe. As before noted, the downward movement of said band frame is not accompanied by any turning of the latter on its axis, since the pawl between the gear 88 and said frame acts to permit said gear to turn independently under the action of the toothed rack 89. This second downward movement of the reversible frame 70 results in the front of the shoe being polished by the polishing band so that by the time the brush carriages 13 have moved to the rear of the casing and have come to rest, the said reversible frame has again been raised to a position with its blacking band ready to engage the front of the shoe.

While I have described the brush carriage and its associated driving mechanism, for operating on one side of a shoe to be polished, there is, as clearly shown in the drawings, a similar assemblage of apparatus for operating simultaneously on the opposite side of said shoe.

What I claim as my invention and desire to secure by Letters Patent is:—

1. In machine for polishing boots or shoes, the combination of rotatable traveling carriages fitted with revolving brushes for polishing the sides of a boot; means for moving said carriages in lines substantially parallel to the lines of a boot; and other means for independently moving said carriages in lines at right angles to said lines to allow the brushes to follow the contour of a boot.
2. The combination in a polishing machine of traveling rotatable carriages; means for moving said carriages in lines substantially parallel to the line of a shoe; other means for independently moving said carriages at right angles to said line; brushes on the carriages; means for revolving the brushes; a ratchet and pawl mechanism for each carriage placed to insure rotation thereof in one direction only; means for polishing the top of the shoe; and a device for moving said last named means out of the path of said carriages.
3. In a machine for polishing boots or shoes, the combination of traveling rotatable carriages; brushes thereon; gearing for revolving said brushes; and means for rotating such carriages to bring each brush in succession into contact with the side portions of a boot, said means comprising stud pins on the upper part of each carriage, crutch

ended rods mounted to coöperate with said pins; a trip bolt mounted to be capable of holding the carriage from rotating; a releasing lever for actuating the bolt; means for treating the top of the boot; and mechanism for periodically moving said latter means out of the path of movement of the carriages.

4. In a polishing machine the combination of a traveling brush carrying structure; a supporting carriage therefor; mechanism for moving the brush carrying structure longitudinally of a shoe; other mechanism for bodily moving said supporting carriage in a line transverse to the shoe; means for reversing the direction of movement of said brush carrying structure, means for treating the top of the shoe; and means for periodically moving said top treating means out of the path of movement of said carriage.

5. In machines for polishing boots or shoes, the combination of means for treating the sides of a shoe; a frame; arms carrying said frame; traveling bands on the frame; means for raising and lowering said frame; means for turning the frame when raised to bring each band in succession into contact with the front of a shoe; said means including a weight and a power actuated carriage operative on the arms to move them in opposite directions; with means for periodically actuating said carriage from said side treating means.

6. In means for polishing boots and shoes the combination of means for treating the sides of a shoe; a frame; traveling bands thereon placed to polish the front of the shoe; means for rotating said frame, the same consisting of a toothed wheel; a curved rack placed to be engaged by said wheel; means whereby said frame is normally held in a definite position; with connections between said frame and the side treating means for periodically causing said parts to move together.

7. In a machine for polishing boots and shoes the combination of means for treating the side parts of a shoe; a frame fitted with shoe treating means; mechanism for causing said means to be brought into contact with the shoe; a carriage operatively connected to said frame; and means for periodically connecting said carriage to the means for treating the sides of the shoe.

8. In a machine for cleaning boots and shoes, the combination of a carriage; a screw shaft and a grooved shaft thereon; a brush supporting structure on said carriage; rails for guiding the carriage; a weight operatively connected to the carriage and tending to move it toward a shoe to be cleaned.

9. A shoe polishing machine having a supporting structure bodily movable toward and from a shoe; a brush carriage movable on said structure at right angles

to the direction of movement of the structure; a series of polishing brushes on said carriage; and means for successively presenting said brushes to a shoe.

10. A shoe polishing machine consisting of a brush carriage having automatic mechanism for moving it in two directions at right angles to each other; a series of brushes mounted on said carriage; means for revolving said brushes; and mechanism for automatically causing said brushes to be successively operative upon a shoe.

11. A shoe polishing machine consisting of a shoe supporting structure; two brush carriages mounted on opposite sides of said structure; means for automatically causing said carriages to be moved longitudinally of a shoe and also toward the same, with a series of brushes carried by each of said carriages, and means for supplying blacking to one brush of each series.

12. The combination in a shoe polishing machine of two brush carriages each having a brush supporting structure and a series of revolute brushes; laterally extending tracks for said carriages; means for automatically moving said carriages on the tracks to move the brushes toward the sides of a shoe; and means for revolving the supporting structure to successively present the brushes to the shoe; with a device for polishing the front of a shoe.

13. The combination in a shoe polishing machine of means for treating the sides of a shoe; a device for polishing the front of the shoe; with means for moving said device in a vertical plane into and out of engagement with the shoe, said means including mechanism for automatically connecting said front polishing device to and disconnecting it from the means for treating the sides of the shoe at predetermined intervals.

14. The combination in a shoe polishing machine of means for polishing the sides of a shoe; with a front polishing device consisting of a frame having shoe treating means; arms rotatably supporting said frame; means including a curved rack and a gear on the frame coöperating with said rack for automatically rotating the frame to present different elements of the shoe treating means to a shoe; means for automatically moving said arms with the frame in vertical planes; and mechanism for actuating the shoe treating means to cause the same to operate on a shoe; with means for periodically connecting and disconnecting the side polishing means and the front polishing device.

15. The combination in a shoe polishing machine of means for polishing the sides of a shoe; with a front polishing device consisting of a frame having shoe treating means; arms rotatably supporting said frame; means for automatically rotating

- the frame to present different elements of the shoe treating means to a shoe; means for automatically moving said arms with the frame in a vertical plane; mechanism for 5 actuating the shoe treating means to cause the same to operate on a shoe; means for supplying blacking to said shoe treating means; said arm rotating means including a relatively fixed member and a coöperating member on the frame; locking means for temporarily retaining the frame in any given position; and means for periodically connecting the side polishing means and the front polishing device.
- 15 16. The combination in a shoe polishing machine of pivotally mounted means for treating the front of a shoe consisting of a support; a frame revolvably mounted on said
- support; endless polishing cloths mounted on said frame; means for driving said cloths; means for automatically revolving the frame to present different cloths to a shoe; means for supplying blacking to one of the cloths to the exclusion of the other; means for polishing the sides of the shoe; 20 and means for periodically connecting the side polishing means and the front treating means.
- In testimony whereof I have signed my name to this specification, in the presence of 25 two subscribing witnesses.

ROBERT MACKINLAY SMITH.
